(57) **CLAIM**

The ornamental design for a vehicle front upper grille as shown and described.

DESCRIPTION

FIG. 1 is a front elevational view of a vehicle front upper grille showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The de-emphasized and relatively light portions of the figures that are separated from the relatively dark portions of the figures by dash-dot broken lines form no part of the claimed design. The areas within the dash-dot broken lines illustrate portions of the vehicle front upper grille that form no part of the claimed design. The dash-dot broken lines form no part of the claimed design.
